UNITED STATES PATENT OFFICE

CHARLES A. BRYANT, OF WAKEFIELD, MASSACHUSETTS.

KNIFE-SCOURER.

SPECIFICATION forming part of Letters Patent No. 293,849, dated February 19, 1884.

Application filed December 20, 1883. (No model.)

To all whom it may concern:

Be it known that I, CHARLES A. BRYANT, of Wakefield, Middlesex county, Massachusetts, have invented a new and Improved 5 Knife Scourer, of which the following is a full, clear, and exact description.

The object of my invention is to provide a new and improved device for scouring and cleaning knives, cutlery, and other articles.

10 The invention consists in the construction and arrangement of parts, as will be herein-after fully described, and then pointed out in the claims.

Reference is to be had to the accompanying 15 drawings, forming part of this specification, in which similar letters of reference indicate corresponding parts in all the figures.

Figure 1 is a perspective view of my improved knife-scourer, showing the manner in 20 which it is used. Fig. 2 is a longitudinal sectional elevation of the same. Fig. 3 is a perspective view of a modified construction of the handle.

A hollow handle, open at the top and closed 25 at the bottom, is provided at its upper end with an apertured cap, B. In the lower end of the handle the stem C of a wire frame, D, is secured, on the cross-piece of which a block, 30 E, of cork, rubber, or other suitable material, is hung or pivoted, the aperture of said block containing a sleeve, F, surrounding the cross-piece of the frame D. The hollow handle can be made tapering, if desired.

The powder for cleaning, scouring, or polishing the knife or other article is filled into 35

the hollow handle. A quantity of this powder is sprinkled from cap B upon the knife or other article to be cleaned, scoured, or polished, and is rubbed on the said article by means of the rubbing-block E.

40 The handle can be held at any desired angle to the blade, thus enabling a greater pressure to be exerted on the block than when the block is held securely on the lower end of the handle, and the hand does not tire as rapidly 45 if my improved cleaner is used as it does if the rubbing-block is held directly on the lower end of the handle.

All four edge-faces of the block E can be used successively, thus permitting of utilizing 50 the entire rubbing-block.

Having thus described my invention, I claim as new and desire to secure by Letters Patent—

1. In a knife-scourer, the combination, with 55 the handle A, of the frame D, secured on the lower end of the same, the rubbing-block E, mounted on the cross-piece of the frame, and of the sleeve F, mounted on the said cross-piece, substantially as herein shown and described.

2. A knife-scourer consisting of the wire 60 frame D, carrying the rubbing-block E, and provided with the tang C, formed by the upper twisted ends of the said frame, and a handle, A, substantially as set forth.

CHAS. A. BRYANT.
